SHEAR DEVICE

Frederick Winterkamp, Youngstown, Ohio

Application February 10, 1934, Serial No. 710,743

9 Claims. (Cl. 164—49)

This invention relates to a shear device, and more particularly to one which is well adapted to the "chopping" or cropping of strip and hoop material before entering a coiling machine, although not limited thereto.

One object of the present invention is the provision of a novel shear device employing levers which will disappear when not in use, and thus prevent damage accruing to the material; which often results in the use of conventional stationary shear knives due to the presence of the shear levers after the "cut" is made.

Another object is to provide a novel device of the class described which is simple in design, and one which will not require adjustment or replacement while in service.

These and further objects will be apparent after referring to the drawings, in which:

Figure 1 is a side elevation of the device of the invention.

Figure 2 is a sectional view on the line II—II of Figure 1.

Figure 3 is a sectional elevation on the line III—III of Figure 1.

Figures 4, 5, 6, 7 and 8 are schematic elevations of the device of the invention in its several stages of operation.

Referring more particularly to the drawings, the numeral 2 designates a bed upon which rests a pair of housing side plates 3, each of which has a vertical aperture 4. The side plates 3 of the housing are provided on their upper edges with a top plate 5 across which the material to be sheared is adapted to be moved. The top plate 5 has an aperture 6 through which the cutting elements of the invention are adapted to appear, effect the cut, and disappear out of view.

Each of the apertures 4 in the side plates 3 is provided with a pair of guide blocks 8, formed of a suitable hard material. A roller 9 is adapted to move in each of the apertures 4 while in contact with the guide blocks 8, and support a shaft 10 which is capable of relative rotary movement. A shear lever 12 is provided intermediate its center and upper end with a journal 13, which is adapted to rotate on a bushing 13^a which is disposed on the shaft 10. The upper end of the shear lever 12, which is indicated at 15, is provided with a knife blade 16. A link 17 is pivoted, as at 18, to the lower end of the shear lever 12. A lug 19 is suitably supported between the side plates 3 and pivotally holds the other end of the link 17, as at 20.

A shear lever 22, which is similar to the shear lever 12, is provided intermediate its center and upper end with a journal 23, which is adapted for rotary movement on a bushing 23^a, the latter being disposed on the shaft 10 similar to the bushing 13^a. The upper end of the shear lever 22, which is indicated at 25, is provided with a knife

blade 26 for cooperation with the knife blade 16 on the shear lever 12 to effect the cutting of the material in a manner to be later described.

The shear lever 22 is apertured adjacent its lower end to enable it to carry a shaft 28 which is adapted to extend from either side thereof and support on each of its ends a bushing 27 on which there is mounted a roller 29. A pair of links 14 are connected on one of their ends to the vertically movable shaft 10, and on the other of their ends to the shaft 28 at positions immediately adjacent the rollers 29. Each of the rollers 29 is adapted to travel on a trackway 30 on each of the side plates 3 of the housing. The trackways 30 are both provided with a curved or arced surface 31. The curved or arced surfaces 31 of the trackways 30 terminate at 32, from whence they extend in a horizontal plane, as shown at 33.

A pair of journals 35 are connected to the bed 2 and rotatably support a shaft 36 having intermediate its ends a crank 37. A pitman 38 is connected to the crank 37 on one of its ends and to the lowermost extremity of the shear lever 22 on its other end, as shown at 39. A gear 41 is secured to one end of the shaft 36.

A pair of journals 43 are suitably secured to the side plates 3 immediately above the journals 35, which are secured to the bed 2, and support a shaft 44 which carries on one of its ends a pinion 45 which is in constant engagement with the gear 41. The shaft 44 carries on its other end a large gear 46. A motor 47 is mounted between the side plates 3 of the housing, and is provided with the usual motor pinion 48, which engages the large gear 46.

Referring to Figure 4 of the drawings, the rollers 29 on the shaft 28, which is carried by the lower end of the shear lever 22, are shown in retracted position adjacent the extremities of the horizontal surfaces 33 of the trackways 30. In this position, the shaft 10 will have been lowered by the shear lever 22 and the links 14, thus retracting the upper ends 15 and 25 of the shear levers 12 and 22, respectively, through the openings 6 in the top plate 5 of the housing.

As the motor 47, through its pinion 48, drives the gear 46 on the shaft 44, and the pinion 45 which engages the gear 41 on the shaft 36, the crank 37, rotating in a clockwise direction, will withdraw the pitman 38 from the position of Figure 4. The withdrawal of the pitman will move the rollers 29 from the horizontal surfaces 33 of the trackways 30 to a position adjacent the upper extremities 32 of the arced or curved surfaces 31, as shown in Figure 5. In this position, the shaft 28, operating through the shear lever 22 and the links 14, will have raised the shaft 10 in such manner as to move the upper ends 15 and 25 of the shear levers 12 and 22, respectively,

through the aperture 6 in the top plate 5 of the housing.

As the crank 37 moves further in its clockwise direction of rotation to the position shown in Figure 6, the rollers 29 will cross the points 32 on the trackways 30 and move down the arced or curved surfaces 31, and cause the upper end 25 of the shear lever 22 to move horizontally toward the upper end 15 of the shear lever 12, bringing their knife blades 26 and 16, respectively, into cutting engagement.

As the cutting engagement of the knife blades 26 and 16 is made, the crank 37 will be in "dead-center" position, from whence it will move in its clockwise direction of rotation, and cause the pitman 38 to move the rollers 29 upwardly over the arced or curved surface 31, as shown in Figure 7, and cause the separation of the ends 25 and 15 of the two shear levers.

20 The further rotation of the crank 37, from the position of Figure 7, will cause the pitman 38 to move the rollers 29 across the points 32, which are uppermost on the arced or curved surfaces 31, and onto the horizontal surfaces 33 of the trackway 30. The movement of the rollers over the horizontal surfaces 33, as shown in Figure 8, will cause the various elements to be restored to the "disappearing" position of Figure 4, thereby completing a cycle of operation.

30 While I have shown and described one specific embodiment of my invention, it will be understood that I do not wish to be limited exactly thereto, since various modifications may be made without departing from the scope of my invention, as defined in the following claims.

I claim:

1. In a shear device, a horizontal shaft adapted for vertical movement, a shear lever carried intermediate its ends by said shaft and adapted for vertical movement therewith, and a second shear lever journaled intermediate its ends on said shaft and adapted for both vertical and rotary movement.

45 2. In a shear device, a housing, a shaft slidably mounted in said housing for vertical movement with respect thereto, a shear lever journaled intermediate its ends on said shaft, a link connected to said housing and to the lower end of said shear lever, a second shear lever journaled 50 intermediate its ends on said shaft, a shear blade mounted on the upper end of each of said shear levers, and means for moving said second named shear lever vertically in such manner as to cause it to partially rotate on said shaft.

55 3. In a shear device, a housing, a shaft slidably mounted in said housing for vertical movement with respect thereto, a shear lever journaled intermediate its ends on said shaft, a link connected to said housing and to the lower end of 60 said shear lever, a second shear lever journaled intermediate its ends on said shaft, a shear blade mounted on the upper end of each of said shear levers, a trackway carried by said housing, a roller carried by the lower end of said second named 65 lever and adapted for movement in said trackway, and means for moving said roller.

70 4. In a shear device, a housing having a vertical aperture in each of its sides, a roller adapted for movement in each of said apertures, a shaft journaled in said roller, a pair of shear levers journaled intermediate their ends on said shaft, means for limiting the rotation of one of said shear levers on said shaft, a curved trackway in

each of the sides of said housing, a shaft carried by the lower end of the other of said shear levers, a roller mounted on each end of said shaft for movement in one of said trackways, a crankshaft journaled on said housing, a connecting-rod carried by said crankshaft and connected to the shear lever carrying the shaft on which said rollers are mounted, and means for rotating said crankshaft.

5 5. In a shear device, a housing having a vertical aperture in each of its sides, a roller adapted for movement in each of said apertures, a shaft journaled in said rollers, a pair of shear levers journaled intermediate their ends on said shaft, means for limiting the rotation of one of said shear levers on said shaft, a curved trackway in 15 each of the sides of said housing, a shaft carried by the lower end of the other of said shear levers, a roller mounted on each end of said shaft for movement in one of said trackways, at least one link connected to both of said shafts, a crankshaft journaled on said housing, a connecting-rod carried by said crankshaft and connected to the shear lever carrying the shaft on which said rollers are mounted, and means for rotating said 20 crankshaft.

25 6. In a shear device, a housing having a vertical aperture in each of its sides, a roller adapted for movement in each of said apertures, a shaft journaled in said rollers, a pair of shear levers journaled intermediate their ends on said shaft, means 30 for limiting the rotation of one of said shear levers on said shaft, a curved trackway in each of the sides of said housing, a shaft carried by the lower end of the other of said shear levers, a roller mounted on each end of said shaft for movement in one of said trackways, a crankshaft journaled on said housing, a connecting-rod carried by said crankshaft and connected to the shear lever carrying the shaft on which said rollers are mounted, and means for rotating said 35 crankshaft, said means comprising a motor and a transmission mechanism.

35 7. In a shear device, a housing having a vertical aperture in each of its sides, a pair of guides in each of said apertures, a roller disposed between each pair of said guides, a shaft journaled in said rollers, a shear lever carried intermediate its ends by said shaft and adapted for vertical movement therewith, and a second shear lever journaled intermediate its ends on said shaft and adapted for both vertical and rotary movement.

45 8. In a shear device, a housing having a vertical aperture in each of its sides, a pair of guides in each of said apertures, a roller disposed between each pair of said guides, a shaft journaled in said rollers, a shear lever carried intermediate its ends by said shaft and adapted for vertical movement therewith, a second shear lever journaled intermediate its ends on said shaft and adapted for both vertical and rotary movement, said housing having an aperture through which said shear levers are adapted to extend in their vertical movement, and a shear blade mounted on the upper end of each of said shear levers.

50 9. A device for shearing strip material comprising a plate across which said material is adapted to be moved, a pair of pivotally connected shear operating levers, a knife-blade on the upper end of each of said shear operating levers, means for operating said levers above said plate, and means for withdrawing said levers below said plate.

FREDERICK WINTERKAMP.
